UNITED STATES PATENT OFFICE.

ANDREW J. ARMSTRONG, OF CHATTANOOGA, TENNESSEE.

RAILWAY-SIGNAL.

SPECIFICATION forming part of Letters Patent No. 599,521, dated February 22, 1898.

Application filed June 19, 1897. Serial No. 641,505. (No model.)

To all whom it may concern:

Be it known that I, ANDREW J. ARMSTRONG, a citizen of the United States, residing at East Chattanooga, in the county of Hamilton and 5 State of Tennessee, have invented a new and useful Railway-Signal, of which the following is a specification.

My invention relates to improvements in railway-signals for use at stations, crossings, 10 bridges, tunnels, and other places where it is desired to give notice to the traveling public of the approach of a train, thereby reducing to a minimum the liability of accidents at crossings and other places.

15 The object of my invention is to provide a simple construction of parts in which an audible signal is actuated mechanically by the wheel-flanges of a passing train; and a further object of my invention is to provide simple means for taking up automatically the slack in the transmitting wires or cables and thus maintain the parts under proper tension, so that they respond quickly to the action of the toggle-bars.

20 To the accomplishment of these ends my invention consists in the novel combination of elements and in the construction and arrangement of parts, which will be hereinafter fully described and claimed.

25 To enable others to understand my invention, I have illustrated the preferred embodiment thereof in the accompanying drawings, forming a part of this specification, and in which—

30 Figure 1 is a perspective view of a railway-signal constructed in accordance with my invention. Fig. 2 is a plan view of a part of a track, illustrating the boxing or housing, the rock-shaft, and the toggle-bars. Fig. 3 is a side view of the parts shown by Fig. 2. Fig.

35 Fig. 4 is a vertical cross-sectional elevation on the plane indicated by the dotted line 3 3 of Fig. 2. Fig. 5 is a detail view of one of the poles and the cable - slack compensator thereon.

40 Fig. 6 is a fragmentary detail view of the adjacent ends of the toggle-bars to show the construction thereof. Fig. 7 illustrates the manner of supporting one of the compensator devices on a telegraph-pole to utilize the latter in the installation of my signal mechanism.

Like numerals of reference denote corre-

sponding parts in all the figures of the drawings, referring to which—

1 and 2 designate the rails, and 3 the cross-ties, of an ordinary railway-track. Between 55 two of the ties of the track I construct a boxing or framework 5, which is bolted or otherwise fastened to the ties. In this boxing is arranged a short rock-shaft 6, which extends across the track and which is suitably journaled in bearings in the frame. The rock-shaft 6 is provided with collars 6', that serve to hold the shaft against endwise movement, and to one of the protruding ends of said shaft is attached an arm 7. On the extremity of 60 65 the arm is mounted a pulley or roller 8, journaled on a stud or pin 9, which is attached to the arm 7. To the opposite end of the rock-shaft 6 from the arm 7 is fastened another arm 10, which is operatively connected to the 70 toggle-bars 11 12.

Adjacent to one of the rails of the track on the outside thereof is fastened a horizontal board 13, and on this board is arranged the toggle-bars 11 12, the latter lying close up to 75 one of the rails. The toggle-bars are arranged substantially in alignment with each other lengthwise of the track, and the outer ends of said toggle-bars are slotted, as at 14, to receive the vertical bolts 15, that pass through 80 the slots and through the footboard 13, whereby the bolts serve to pivotally support the toggle-bars on the footboard. Each toggle-bar is flanged at the side adjacent to the track-rail, as at 16, and the adjacent or meeting ends of 85 said toggle-bars are cut away at opposite sides to form the shoulders 17 and the recesses 18, thus enabling the toggle-bars to overlap one another at the meeting ends thereof. Said toggle-bars are further provided on their 90 lower sides with integral or rigidly-attached arms 19 20, and these arms are recessed to enable them to lap one another.

The toggle levers or bars 11 12 are operatively connected with the arm 10 of the rock-shaft 6 by means of the link 21. This link is arranged in a vertical position, and it passes through and plays in a vertical slot 21', provided in the footboard 13. The lower end of the vertical link is forked to straddle the extremity of the arm 10, and the link and arm are pivotally connected by a transverse pin or

bolt 22. The upper end of the link 21 is also forked or bifurcated to straddle the overlapping ends of the arms 19 20 of the toggle-bars, and said link and the toggle-bars are 5 pivotally attached by a transverse pin or bolt 23, which passes through the forked end of the link and through the overlapped ends of the arms 19 20 of the toggle-bars. By this construction I am enabled to attach the toggle-bars to the rock-shaft in a manner to prevent the wheel-flanges from striking the pivotal joint between the toggle-bars and the connecting-link, said joint lying below the exposed faces of the flanged toggle-bars. The 10 toggle-bars and the link are connected together by a single pivotal pin or bolt, and the joints are lapped to reduce to a minimum any wrenching strain on the parts exposed to the pressure and weight of the passing train.

15 The toggle-bars are normally raised to inclined positions above the face or top of the track-rail by means of pressure-springs 25, which are seated upon the footboard 13 and against the toggle-bars. The said toggle-bars 20 are thus presented or exposed above the track-rail for the wheel flanges or treads to ride thereon, and by having the top faces of the toggle-bars flanged adjacent to the head of the track-rail the flanges of the wheels have 25 a tendency to press the toggle-bars inward toward and against the head of the track-rail, thus obviating any outward pressure upon the toggle-bars by the wheel-flanges riding between the toggle-bars and the track-rail and reducing the tendency to wrench and 30 displace the toggle-bars.

35 At suitable intervals along the side of a track I erect a series of poles or uprights 27, 28, and 29, the last-named pole, 29, being situated adjacent to the tunnel, crossing, station, or other place where it is desired to warn the public by an audible signal of the approach of a train. These posts or uprights may be arranged at suitable distances apart, and 40 when a telegraph-line is adjacent to the track I may dispense with one or more of the poles 27 or 28 and utilize in lieu thereof one or more of the telegraph-poles. The poles 27 are equipped with guides through which leads or 45 runs the connecting wire or cable; but on one or more of the posts 28 I provide the compensator 31, that operates to take up any slack in the wire or cable and to maintain the latter taut under all conditions of service. One 50 or a series of these compensators may be used in my mechanical signaling system, according to the length of the connecting wire or cable and the tension it is desired or necessary to maintain in said wire or cable. Each 55 compensator device has a frame 32 of any suitable form, a rock-shaft 33, a weighted pendant 34, and an arm 35. I may cast the rock-shaft, its weighted pendant, and the arm in one single piece, thus simplifying and 60 cheapening the construction. The frame 32 is provided with suitable bearings to receive the terminals of the rock-shaft, and the lat-

ter is thus pivotally mounted on the frame to swing or rock therein. I preferably arrange the shaft to have the weight hang downwardly therefrom, while the arm 35 extends upwardly from the shaft.

65 The conducting wire or cable 36 has one end attached to the pulley or roller 8. From this pulley the wire or cable runs through 70 the guides on the poles 27, and it is attached to the arms 35 of the rock-shafts, forming parts of the compensator devices. The other end of the wire or cable is connected to an 75 audible signal or alarm device 30, provided 80 on the pole 29. This signal may be of any suitable kind; but I prefer to use a bell, which is carried by a rock-shaft 30', the latter having an arm 30", to which arm the remote end of the wire or cable 36 is connected 85 in a suitable way.

90 This being the construction of my improved railway-signal the operation may be described as follows: The bell or other signal normally remains at rest, with the wire or cable 36 held 95 under tension by the compensator devices, and the toggle-bars 11 12 are raised slightly above the track by the action of the springs. As a train approaches a crossing the wheel-flanges ride upon the raised ends of the 100 toggle-bars and bear against the flanges thereof to press said bars inwardly against the rail. The weight of the passing wheels on a train of cars imparts vertical impulses in a downward direction to the toggle-bars against the 105 tension of the springs thereof, and these impulses or vibrations are transmitted by the link to the rock-shaft. The rock-shaft pulls on the cable or wire 36 to overcome the gravity of the compensator-weights, and said wire 110 or cable thus actuates the signal-bell to sound the alarm. The signal is actuated automatically so long as the cars operate upon the 115 toggle-bars, and the signal thus sounds continuously while the train approaches the 120 crossing, tunnel, bridge, or other place to warn the public of the approach of the train.

125 In Fig. 7 of the drawings I have illustrated one of the compensator devices mounted upon a telegraph-pole adjacent to the track. The 115 rock-shaft of the compensator is journaled in suitable bearings on one of the cross-arms or trees of the telegraph-pole, and this rock-shaft carries the arm to which the connecting 120 wire or cable is attached and the weighted pendant that operates to hold the cable under tension.

130 Various changes may be made in the form and proportion of parts without departing from the spirit of my invention.

Having thus fully described my invention, what I claim as new, and desire to secure by Letters Patent, is—

1. In a mechanical railway signal system, the combination of spring-actuated toggle-bars adjacent to one of the track-rails, a distant audible signal, a series of pendulum-compensators intermediate of the toggle-bars and the distant signal, and a connecting wire

or cable having its terminals operatively connected with the signal and the toggle-bars, and connected at points intermediate of its length with said pendulum-compensators, as 5 and for the purposes described.

2. In a signaling system, the combination of a rock-shaft arranged below the track, a pair of toggle-bars situated adjacent to a track-rail and provided on their sides next 10 to the track-rail with longitudinal, flange-engaging ribs, a link connected with said toggle-bars and with the rock-shaft, and a distant signal operatively connected, by intermediate mechanism, with said rock-shaft, as 15 and for the purposes described.

3. In a signaling system, the toggle-bars provided with the longitudinal flanges, and with the arms on the lower sides thereof; the adjacent ends of said flanged bars and the 20 arms thereof constructed to overlap one another, combined with a rock-shaft, a link which embraces the lapped ends of said arms and is pivotally attached to said arms and to the rock-shaft, and a signal device operatively connected with the rock-shaft, as and for the 25 purposes described.

4. In a signaling system, the combination with toggle-bars, and a rock-shaft, of a dis-

tant signal device, a pendulum-compensator having a weighted pendant and an arm on a 30 common rock-shaft, and a connecting wire or cable attached at its ends to the rock-shaft and the signal, and connected at a point intermediate of its length to the arm of the pendulum-compensator device, as and for the 35 purposes described.

5. In a railway signaling system, the combination of a pair of spring-pressed toggle-bars, a rock-shaft, a vertical link connecting said rock-shaft with the toggle-bars, a series 40 of posts, a series of pendulum-compensator shafts mounted on certain of the posts, and each shaft carrying a weighted pendant and an arm, a distant signal, and a connecting wire or cable attached at its ends to the rock- 45 shaft and to the signal, and connected at points intermediate of its length to the arms of the pendulum-compensator shafts, as and for the purposes described.

In testimony that I claim the foregoing as 50 my own I have hereto affixed my signature in the presence of two witnesses.

ANDREW J. ARMSTRONG.
